UNITED STATES PATENT OFFICE.

HULDREICH KELLER, OF BERLIN, GERMANY, ASSIGNOR TO GENERAL ELECTRIC COMPANY, A CORPORATION OF NEW YORK.

CENTRIFUGAL PUMPING APPARATUS.

1,008,601.

Specification of Letters Patent. Patented Nov. 14, 1911.

Application filed October 14, 1907. Serial No. 397,271.

To all whom it may concern:

Be it known that I, HULDREICH KELLER, a citizen of Switzerland, residing at Berlin, Germany, have invented certain new and useful Improvements in Centrifugal Pumping Apparatus, of which the following is a specification.

The present invention relates to centrifugal pumping apparatus, and has for its object to provide an apparatus of improved construction which is capable of effectively withdrawing air, vapor, etc., from the exhaust steam of a reciprocating engine or a turbine as it is being condensed in a condenser, and this without an undue expenditure of power or mechanical complication. The invention is not however limited to this particular use, being adapted for exhausting rarefied fluid from any region of low-pressure.

In the accompanying drawing Figure 1 shows partly in section and partly in elevation one of the embodiments of my invention; Fig. 2 is a similar view of a modification; Fig. 3 is a section on the line 3—3 of Fig. 1; and Fig. 4 is a section on the line 4—4 of Fig. 1.

Mounted upon the upper end of the main shaft 1 is a driving motor 2 having the usual means for sustaining the shaft in its proper position.

Mounted directly on the shaft below the motor is the impeller 3 of a "throwing" air pump, and below that is the impeller 4 of a centrifugal pump which may be of the single or multistage type. The impellers which have suitably shaped vanes may be located in separate casings with suitable connecting conduits, or in the same casing with the necessary partitions and passages, the latter being the preferred construction. The casing 5 is divided into sections so as to permit of assembling the parts.

Surrounding the impeller of the air pump is a ring 6 containing a plurality of suitably shaped outwardly-extending vanes with passages 7 between. The air, vapor, etc., to be extracted enters the chamber 8 of the pump casing through the conduit 9, the latter being connected to the condenser or other vessel from which it is desired to pump said air, vapor, etc. Water or other fluid enters the pump chamber 10 by the conduit 11, and falls on the impeller from which it is thrown outwardly by the vanes as the

latter rotates. The water can only act on the air after it has passed through the impeller on account of the annular wall of the pump chamber. The several columns of water discharged by the impeller enter each of the vane spaces in the stationary ring in the form of pistons separated by spaces more or less great. As this action takes place the air from the chamber 8 is so to speak pocketed between the water pistons and is withdrawn from the system connected to the conduit 9. In other words, water from the chamber 10 is divided into many jets by the large number of buckets or vanes on the impeller, and these jets are divided into a large number of pistons by means of the vanes or buckets in the ring 6. The water particularly as it passes out from the ring 6 becomes intimately mixed with the air.

The compressed air and the water discharged from the vane spaces in the ring 6 enter the annular collection chamber 12 and the mixed fluids are conveyed by one or more conduits 13 through the neck 14 to the impeller 4 of the centrifugal pump. It will be observed that the conduits 13 and the impeller 4 are separate from the throwing pump by the partition 15.

The mixture of water and air from the collection chamber enters the impeller 4 and by the latter is forced outwardly through the collecting ring 16 which is provided with a plurality of outwardly extending vanes or buckets with vane spaces 17 between. It is then collected in the annular chamber 18 and discharged by the conduit 19. The vanes are designed according to well known principles to suit the conditions under which the pump operates.

If it is only desired to raise the air out of a vacuum against atmospheric pressure, as a rule a single stage centrifugal pump is sufficient. If, however, in addition to opposing atmospheric pressure, the throwing water has to be delivered at any considerable height then two or more impellers 4 are employed as shown in Fig. 2.

The main shaft for the apparatus may be horizontal instead of vertical. The pumps may be driven separately by suitable motors instead of together as shown.

As regards capacity for suction centrifugal pumps are considerably inferior to throwing pumps although in some respects

for certain conditions of service centrifugal pumps are superior to throwing pumps. The outwardly thickened vanes of the throwing pumps cause the throwing water 5 to pass outwardly in individual jets which are separated into pistons by the vanes of the outer conducting ring. These pistons suck the air, vapor, etc., from the condenser or other region of low pressure and com- 10 press or condense it substantially as if they were rigid pistons. In this manner a rarefaction of the air or a degree of vacuum can be obtained which is very close to that which is theoretically possible.

15 The present invention combines the advantages of the two pumps, namely, the superior suction action of the throwing pump, with the superior operation of the centrifugal pump for conveying and at the same 20 time compressing or condensing to a high degree air of a certain initial specific weight or density without great friction losses. In other words, the invention utilizes the very efficient suction action of a throwing pump 25 to draw rarefied air or vapor, or a mixture of both, from a condenser or other region of low pressure, said throwing pump also compressing the elastic fluid drawn into it by such action and delivering it at a pres- 30 sure that is best suited for efficient handling in the centrifugal pump by which it is drawn from the discharge of said throwing pump and delivered to any suitable region. If it were attempted to draw rarefied elastic 35 fluid directly from the condenser by means of a centrifugal pump, said fluid would be in such condition that it could not be han- 40 dled efficiently by a pump of that type. By means of the improved apparatus above de- 45 scribed, the rarefied fluid is efficiently han- 50 dled and the working of the system of which the apparatus forms a part is greatly im- 55 proved.

I do not claim herein the specific con- 45 struction of parts shown in Figs. 3 and 4 of the drawing, but use them merely as illustrations of suitable structures that may be incorporated in my improved pumping apparatus. The structure illustrated in Fig. 50 3 is claimed in my United States Patent No. 987,994, dated March 28, 1911.

In accordance with the provisions of the patent statutes, I have described the principle of operation of my invention together 55 with the apparatus which I now consider to represent the best embodiment thereof: but I desire to have it understood that the apparatus shown is only illustrative, and that the invention can be carried out by other 60 means.

What I claim as new and desire to secure by Letters Patent of the United States, is:

1. In an apparatus of the character de- 65 scribed, the combination of a throwing pump, a conduit through which elastic fluid

is drawn by suction into the casing of said pump from a region of relatively low pressure, a conduit which admits liquid to the impeller of the throwing pump for coöperation therewith to draw in elastic fluid 70 through the first conduit and increase its density, a centrifugal pump which draws the compressed fluid from the discharge of the throwing pump, and a delivery conduit for said centrifugal pump. 75

2. In an apparatus of the character de- 80 scribed, the combination of a throwing pump, a conduit through which elastic fluid is drawn by suction into the pump casing from a region of relatively low pressure, a conduit which supplies liquid to the pump impeller for coöperating with the pump to draw in elastic fluid from the first conduit and increase its density, means arranged to receive the liquid and the compressed elastic fluid from the pump, a centrifugal pump which draws its supply from the contents of said means and increases its pressure, and a discharge conduit for said centrifugal pump. 85

3. In an apparatus of the character de- 90 scribed, the combination of a throwing pump, a centrifugal pump arranged to receive the discharge therefrom, a casing com- 95 mon to the pumps, a conduit for supplying liquid to the impeller of the throwing pump, a conduit through which elastic fluid is drawn by suction into the casing of the throwing pump from a region of relatively low pressure, said fluid being compressed by the liquid to a degree sufficient to enable 100 it to be handled efficiently by the centrifugal pump, a conduit through which the discharge of the throwing pump is drawn into the centrifugal pump, and a discharge conduit for the latter pump. 105

4. In an apparatus of the character de- 110 scribed, the combination of a throwing pump, a multi-stage centrifugal pump which receives the discharge of the throw- 115 ing pump, a conduit for supplying liquid to the impeller of the throwing pump, a conduit through which elastic fluid is drawn by suction into the casing of the throwing pump from a region of relatively low pressure, a discharge conduit for the centrifugal pump, and a shaft that is common to the im- 120 pellers of both pumps.

5. In an apparatus of the character de- 125 scribed, the combination of an impeller, a ring receiving the discharge therefrom, vanes in said ring, a conduit admitting liquid to the receiving ends of the impeller vanes, a conduit through which elastic fluid is drawn by suction from a region of relatively low pressure and passes to the receiving ends of the vanes in the ring to be compressed therein by liquid thrown from the impeller, a casing for the impeller and ring containing a collection chamber, a centrifugal pump having a casing, a conduit through 130

which liquid and compressed fluid are drawn from the chamber into the inlet of the centrifugal pump, and a discharge conduit for the latter pump.

6. In an apparatus of the character described, the combination of a throwing pump, comprising a shaft, an impeller on the shaft having a suction inlet adjacent said shaft and passages leading therefrom to the periphery of the impeller, a ring surrounding the impeller and provided with passages into which it discharges, a casing for the pump having a chamber in which the impeller rotates, a suction chamber adjacent the suction inlet, a diaphragm arranged adjacent the impeller on the side opposite to the suction chamber, an annular chamber surrounding the ring into which the pump discharges, and a discharge outlet leading from said chamber, a conduit supplying liquid to said suction chamber, a conduit connected with the impeller cham-

ber through which rarefied elastic fluid is drawn from a region of relatively low pressure and compressed by the action of the 25 liquid in the pump, the liquid and compressed fluid being discharged from the ring into said annular chamber, a centrifugal pump having a suction inlet adjacent the discharge outlet of the annular chamber, 30 there being passages in the casing between the outer wall thereof and the diaphragm leading from said annular chamber to the discharge outlet, a casing for the centrifugal pump which is connected to the casing of 35 the throwing pump, and a discharge conduit leading from said casing.

In witness whereof, I have hereunto set my hand this 19th day of September, 1907.

HULDREICH KELLER.
